PROCESS OF MAKING BULLETS

John H. Friedman, Tiffin, Ohio, assignor to The National Machinery Company, Tiffin, Ohio, a corporation of Ohio

Application May 16, 1941, Serial No. 393,727

9 Claims. (Cl. 29—1.22)

This invention relates to projectiles, and more particularly to a bullet core and a process of making the same.

The principal object of this invention is to increase the penetrating power of projectiles, particularly small-calibre rifle and machine gun bullets. Bullets of this type designed to pierce armor plate have been made of a steel core encased in a jacket. The characteristics of the core determine the penetrating ability of the bullet, and the present invention provides a substantial increase in penetrating ability as compared with other types of cores and methods of making the same. Other objects are to decrease the cost of such bullets and cores, and decrease the time required for fabricating the same. Other objects and advantages will appear from the following description of the preferred embodiment of the invention.

In the accompanying drawing:

Figure 1 is a sectional view through a double blow header showing the completion of the first step in making a bullet or bullet core according to this invention;

Figure 2 is a similar view showing the second step;

Figure 3 is an elevation of a cut off wire or rod blank;

Figure 4 is an elevation of the blank formed by the first step;

Figure 5 is an elevation of the blank formed by the second step;

Figure 6 is an elevation of a completed bullet or bullet core cut longitudinally and etched and showing the flow lines of the metal;

Figure 7 is a cross section through a completed jacketed bullet.

I have illustrated suitable punches and a die for carrying out my novel method in a conventional double blow solid die cold header of the type commonly used for making bolts and similar headed articles. Such machines include a frame carrying a fixed solid die; a reciprocating slide carrying two punches, each of which is alined with the die on alternate strokes of the slide; means for cutting off blanks from wire or rod stock and carrying a fresh blank into alinement with the die before each operating stroke of the first punch; and means for ejecting the blank from the die after each operating stroke of the second punch. A high speed machine of this type which may be used to carry out the present process is illustrated in the patent to Clouse, No. 1,932,396. A suitable blank cut-off and carry-over mechanism is shown in the patent to Clouse

No. 1,856,028, and a suitable knockout in the patent to Clouse No. 1,968,128. It will be understood, however, that any desired type of machine may be employed.

5 The die 10, shown in Figures 1 and 2, is mounted in the frame of a header and is arranged to receive cylindrical blanks 11 (Figure 3) which are carried into alinement with the die by the cut-off mechanism of the machine. A knock-out rod 12 is slidably mounted in the die, its forward end forming the bottom of the die during the working of the blank. The die is formed with a cylindrical portion 13 adjacent its forward face which is of greater diameter than the stock 11, and, 15 when the bullet is to be formed with a boat-tail, a conical portion 14 tapering down to a diameter less than the stock diameter.

The header slide, which is reciprocable toward and away from the die 10, carries a movable portion 15 on which are mounted a pair of punches 16 and 17. Preferably the punches are mounted as disclosed in my prior Patent No. 1,955,061 in order to insure accuracy. In the normal operation of the machine, the punch 16 alined with the 20 die after a fresh blank has been cut off and positioned in front of the die, and the header slide on its forward stroke then pushes the blank into the die and carries out the first operation, the parts at the end of this stroke being arranged 25 as shown in Figure 1. For the next forward stroke the punch 17 is alined with the die, the blank remaining in the die, and at the completion of this stroke the parts are arranged in the position 30 shown in Figure 2.

35 In the embodiment illustrated the punch 16 is provided with a cylindrical opening 18 of substantially the same diameter as the stock and a conical portion 19 communicating therewith and tapering down to a diameter smaller than the stock diameter. The punch 17 is provided with an opening 20 which, at the front face of the punch, is substantially the same diameter as the opening 13 in the die 10, and which is formed with an ogival or other shape which it is desired to im- 40 part to the front end of the bullet or bullet core.

In order to insure the blank remaining in the die and not sticking to the walls of the opening in the punch either or both of the punches may be provided with a suitable knockout mechanism.

50 As illustrated the punch 16 is provided with an axial bore communicating with the end of the conical opening 19 and slidably supporting a knockout rod 21. At its rear end the rod 21 is provided with a head 22 thrusting against a compression spring 23, the other end of which is

seated upon an abutment portion 24 which is solidly mounted upon the punch carrier 15. A sleeve 25 is illustrated surrounding the spring 23 and the head 22 and abutting against the rear end of the punch 16 and the forward face of the solid abutment 24. The punches are fixed in the punch carrier by bolts or any other suitable fastening means (not shown) and with the arrangement illustrated the knockout rod 21 is free to be pressed rearwardly when it is engaged by the end of the blank at the completion of the first stroke of the header as illustrated in Figure 1. When the header slide recedes from the position illustrated in Figure 1 the tension of the spring 23 frees the blank from the walls of the punch so that the blank remains in the die for the next operation.

My novel process in its preferred form is illustrated by Figures 3 to 6 showing the successive stages of the blanks. The blank 11 as cut off from wire or rod stock has a diameter a and a length substantially greater than the length of the completed bullet. In the first blow the end of the blank which enters the die is partially extruded and partially upset into a conical portion 26, forming the boat-tail of the bullet. I use the term "extruding" to describe the type of forging operation in which the stock is forced into and caused to slide along the wall of a die smaller than the stock, thus decreasing the diameter and increasing the length of the stock. This type of forging gives a distinctive structure to the metal, somewhat similar to the surface effect of wire drawing, except that the metal is worked throughout and improved physical properties are imparted to it. I use the term "upsetting" to designate the type of forging in which the metal is expanded in diameter and decreased in length by endwise pressure. The extreme end of this portion 26 has a diameter b smaller than the stock diameter. The remainder of the portion of the blank which enters the die is upset into a substantially cylindrical portion 27 merging into the larger end of the conical portion 26 and having a diameter c greater than the stock diameter. The opposite end of the blank enters the conical portion 19 in the punch 16 and is extruded into a conical end 28. The remainder of the blank fits within the cylindrical portion 18 of the punch 16 and is retained as a cylindrical portion 29 having substantially the diameter a of the original stock. It will be understood that on this first blow the cylindrical portion 27 of the blank may not be completely filled out into the cylindrical portion 13 of the die 10, since it is only necessary to impose sufficient pressure on the blank to upset and extrude the conical end 26 and extrude the conical end 28. Thus to make certain that the blank remains in the die when the header slide retracts after the first blow, the punch 16 may be provided with the knockout rod 21 as described above.

On the second blow the conical portion 28 at the front end of the blank is further extruded to reduce the extreme end 31 to a relatively small diameter. I permit this extreme end 31 to extrude into a small diameter cylindrical bore in the punch in the preferred embodiment, as illustrated in Figures 2 and 5, in order to limit the pressure on the tools and provide an escape for any excess volume of metal in the blank without throwing an excessive flash at the face of the die 10. The cylindrical portion 29 is upset into the cavity 20 in the punch 17 so that the portions 28 and 29, by the combined extruding and

upsetting action, are brought to a substantially ogival shape indicated at 30 in Figure 5. The cylindrical portion 27 and the conical end 26 remain substantially unchanged except that they may be more completely filled out into full sharp contact with the walls of the die by the increased pressure of the second blow. After the second operation the header slide again recedes and the finished blank, as illustrated in Figure 5, is ejected from the die 10 by the knockout rod 12.

Any flash that may be formed at the junction of the cylindrical portion 27 and the ogival nose 30 at the face of the die may be knocked off in any convenient manner. The extreme end 31 of the blank may then be formed into a point 32 in any suitable manner, as by a turning operation. The finished blank 33 may then be used as a bullet, or, in accordance with the usual practice, may be enclosed in a jacket 34 to form the finished bullet. The operations are preferably carried out by "cold working" or working below the temperature of rapid grain growth or recrystallization. The stock may be at ambient temperature, and although the temperature of the blank is raised by the working operations it ordinarily does not exceed 400 to 500 degrees Fahrenheit. This cold forging hardens, strengthens, and compacts the metal and refines the grain structure, increasing the resistance to impact and consequently the penetrating ability.

In addition, in metal working operations, "flow lines" are created extending in the direction in which the metal was caused to flow during the working. These flow lines give a directional effect to the metal, increasing the tensile strength in the direction of the flow lines and the shear resistance in a direction transverse to the flow lines. Ordinary rolled rod or drawn wire stock embodies flow lines produced by the hot rolling of the material which extend axially of the stock and substantially parallel to each other. Thus when such stock is cut to form an ogival or pointed end the flanks of the point or ogive intersect or cut across the flow lines, leaving the ends exposed. When such a pointed end attempts to pierce or penetrate metal the decreased shear strength along the direction of the flow lines is opposed to the shearing and abrasive action of the metal being penetrated, resulting in a breaking up and failure of the metal of the projectile and dissipation of its energy.

Bullets fabricated in accordance with the present process, however, have the flow lines substantially conforming to the contour of the bullet, as illustrated in Figure 6. The extrusion of the end of the stock deeply and thoroughly works the metal by bunching the flow lines and drawing them toward a point. The upsetting of the stock in the cylindrical portion 29 similarly works the metal thoroughly and spreads the flow lines outwardly to the maximum diameter c . A similar effect is produced on the conical portion 26 or boat-tail of the bullet. Thus the bullet produced in accordance with the present invention has the maximum strength which can be developed in the metal opposed to the abrasive and shearing forces acting upon the ogive when the bullet penetrates armor or other solid material, so that the bullet penetrates through a substantially greater depth of armor plate or the like before the energy of the bullet is dissipated or the metal of the bullet fails.

While the extreme point 32 of the ogive may be formed by cutting a point in the extruded end 31 of the blank, no substantial loss of penetrating

ability is effected because the diameter of the extruded end 31 is but a small fraction of the total diameter and the metal is confined by the surrounding extruded and upset metal. In addition the end 31 receives the greatest amount of working and thus has maximum hardness and strength.

Preferably the conical end 28 formed on the blank by extrusion in the first punch 16 is of such angle and length as to insure thorough working of the metal throughout the ogive by the second blow, so as to develop the improved metal properties resulting from the cold forging throughout this portion of the bullet. In the illustrated embodiment the taper of the conical portion 28 is less than the taper of the ogival cavity 20 in the portion of that cavity having a diameter equal to, and less than, the diameter of the small end of the portion 28. Thus the punch 17 first contacts the extreme end of the blank and applies the upsetting force to the entire blank. As the punch 17 advances toward the die, all of the metal of the conical portion 28 and of the cylindrical portion 29 starts to upset. As the resistance to upsetting increases, the forward end of the conical portion 28 begins to crawl down into the smaller portion of the cavity 20, ultimately extruding into the cylindrical end 31. Thus the major portion of the flank of the ogive is formed by metal which is both extruded and upset, and the portion of smaller diameter than the diameter of the end of the conical portion 28 is first extruded in the punch 16, then upset, and finally extruded in the punch 17.

The same effects are obtained when the bullet is encased in a jacket 34. The jacket may be drawn from a corrosion resistant material which serves as a lubricant and aids in starting the bullet into armor plate and the like as is customary in armor piercing artillery projectiles. When the bullet strikes the jacket promptly disintegrates and the penetration is effected by the core.

It will be understood that the bullets or bullet cores may be manufactured in accordance with this process from any suitable material. Ordinary medium carbon steel has been found to be satisfactory from the standpoint of density and toughness and is also readily worked in the cold forming operations of my invention. Other materials having special properties to meet particular conditions may, however, be used.

Although a preferred embodiment of my invention has been described in considerable detail it will be understood that many variations and modifications may be resorted to without departing from the scope of the invention as defined in the following claims.

I claim:

1. The process of making a bullet from a cylindrical blank of wire or rod stock comprising in one operation forging an end of the blank to reduce its diameter, upsetting another portion of the blank to increase its diameter, and maintaining an intermediate portion of the blank at substantially its original diameter, and, in an other operation, upsetting said forged end and said intermediate portion and further forging said end to form an ogive.

2. The process of making a bullet from a blank of substantially cylindrical stock comprising confining an intermediate portion of the length of the blank to maintain the same at substantially its original diameter upsetting an adjacent portion of the blank to form a substantially cylindrical portion of larger diameter than the diam-

eter of the stock, and upsetting and forging said intermediate portion and the adjacent end portion of the blank to form a pointed end merging into said substantially cylindrical portion.

3. The process of making a bullet from a blank of substantially cylindrical stock comprising confining an intermediate portion of the length of the blank to maintain the same at substantially its original diameter upsetting a portion of the blank on one side of said intermediate portion to form a substantially cylindrical portion of larger diameter than the diameter of the stock, forging the end portion of the blank on the other side of said intermediate portion to form a conical portion, and further forging and upsetting the said intermediate portion and the said conical portion of the blank to form a pointed end merging into said substantially cylindrical portion.

4. The process of making a bullet from a blank of substantially cylindrical stock comprising upsetting a portion of the blank to form a substantially cylindrical portion of larger diameter than the diameter of the stock, forging an end of the blank to form a conical portion spaced from said substantially cylindrical portion by an intermediate length of substantially the original diameter of the blank, and upsetting the forged end and intermediate length to form a pointed end merging into said substantially cylindrical portion.

5. The process of making a bullet from a blank of substantially cylindrical stock by cold working, comprising upsetting a portion of the blank into a cylindrical body of larger diameter than the stock, forging an end of the blank to form a conical portion while maintaining the length of the blank between said body and said conical portion at substantially the original diameter of the blank, and upsetting said conical portion and said length of the blank to form a nose merging with said body and tapering to a diameter smaller than the stock diameter.

6. The process of making a bullet from a blank of substantially cylindrical stock comprising enclosing an intermediate portion of the length of the blank in a cylindrical die opening of substantially the same diameter as the blank so as to maintain said intermediate portion at substantially its original diameter, upsetting one end of the blank beyond said intermediate portion into a die opening to form a substantially cylindrical upset portion of greater diameter than the original diameter of the blank and in another operation upsetting the opposite end of the blank and said intermediate portion into a pointed end merging with said upset portion.

7. The process of making a bullet from a blank of substantially cylindrical stock comprising enclosing an intermediate portion of the length of the blank in a cylindrical die opening of substantially the same diameter as the blank so as to maintain said intermediate portion at substantially its original diameter, upsetting one end of the blank beyond said intermediate portion into a die opening to form a substantially cylindrical upset portion of greater diameter than the original diameter of the blank and, while said cylindrical upset portion is retained in its die opening, upsetting the opposite end of the blank and said intermediate portion into a pointed end merging with said cylindrical upset portion.

8. The process of making a bullet from a blank of substantially cylindrical stock comprising enclosing an intermediate portion of the length of

the blank in a cylindrical die opening of substantially the same diameter as the blank so as to maintain said intermediate portion at substantially its original diameter, upsetting one end of the blank beyond said intermediate portion into a die opening to form a substantially cylindrical upset portion of greater diameter than the original diameter of the blank and, while said cylindrical upset portion is retained in its die opening, upsetting and extruding the opposite end of the blank and said intermediate portion into a pointed end merging with said upset portion.

9. The process of making a bullet from a blank of substantially cylindrical stock comprising 15

5 enclosing an intermediate portion of the length of the blank in a cylindrical die opening of substantially the same diameter as the blank so as to maintain said intermediate portion at substantially its original diameter, upsetting one end of the blank beyond said intermediate portion into a die opening to form a substantially cylindrical upset portion of greater diameter than the original diameter of the blank, forging 10 the opposite end of the blank beyond said intermediate portion, and thereafter upsetting the forged end of the blank and said intermediate portion into a pointed end merging with said upset portion.

JOHN H. FRIEDMAN
